UNITED STATES PATENT OFFICE.

RAY P. JACKSON, OF WILKINSBURG, PENNSYLVANIA, ASSIGNOR TO WESTINGHOUSE ELECTRIC & MANUFACTURING COMPANY, A CORPORATION OF PENNSYLVANIA.

CURRENT-COLLECTING DEVICE.

995,145.

Specification of Letters Patent. Patented June 13, 1911.

Application filed April 12, 1906, Serial No. 311,268.

To all whom it may concern:

Be it known that I, RAY P. JACKSON, a citizen of the United States, and a resident of Wilkinsburg, in the county of Allegheny and State of Pennsylvania, have invented a new and useful Improvement in Current-Collecting Devices, of which the following is a specification.

My invention relates to current collectors 10 that are employed upon railway vehicles and particularly to such as are adapted to engage third rails or similar supply conductors.

The object of my invention is to provide 15 a current collector that shall be adapted to engage a third rail that is disposed in either right-side-up or inverted position and which may be moved to such inactive position, when not in use, that it will not protrude 20 beyond the outline of the vehicle in connection with which it is employed.

Figure 1 of the accompanying drawings 25 is a view, in front elevation, of a current collecting device that is constructed in accordance with my invention and Fig. 2 is a vertical, sectional view of the device on the line II—II of Fig. 1.

Secured by means of bolts 1 to a wooden or other insulating bar 2 that is carried in a suitable manner by the body or other part of a vehicle, (not shown) is a bracket 3 having downwardly extending arms 4 and 5 in the extremities of which a pivot pin or rod 6 is loosely fitted. The corresponding ends 30 of a plurality of links 7 are secured to the rod 6 at intervals by means of pins 8, another rod 10 being similarly secured in the other ends thereof. Loosely pivoted upon the rod 10 are contact arms or shoes 11 and 12, the free ends of which are of a suitable 35 form to enable them to engage a third rail (not shown) in either right-side-up or inverted position. The rod 10 is surrounded at intervals by helical springs 13 the ends of 40 which are crossed and disposed upon opposite sides of pins 14 that are formed integral with or are secured to the extremities of the links 7. The springs thus serve as resilient means for opposing pivotal movements of 45 the arms 11 and 12 upon the rod 10 and also cause them to exert pressure upon the third rail with which they are adapted to engage 50 regardless of variations in its height. The contact arms or shoes are connected to a ter-

minal piece 15 that is mounted upon the bar 2 by means of flexible conductors 16.

A U-shaped bracket 17, the extremities of which are also loosely pivoted upon the rod 10, is connected by means of a piston rod 18 to a piston 19 within a cylinder 20, that 60 is secured to the bracket 3 by means of bolts 21. The contact arms or shoes are normally maintained in the positions indicated in broken lines by means of a helical compression spring 22 that is interposed between the 65 lower side of the piston 19 and the end of the cylinder 20, and are moved to the positions shown in full lines when fluid-pressure is admitted to the cylinder above the piston through a suitable supply pipe 23. When 70 the parts occupy the former position, they do not protrude beyond the outline of the vehicle in connection with which they are employed and consequently are not liable to injury that might be caused by striking objects located close to the tracks upon which 75 the vehicle operates.

Since the structural details and arrangements of the parts may obviously be varied within considerable limits from what has 80 here been specifically shown and described without altering the mode of operation of the invention or departing materially from its spirit, I desire that only such limitations shall be imposed as are expressly set forth 85 in the appended claims.

I claim as my invention:

1. A current collector having a pivotally mounted contact arm comprising two pivotally connected members, resilient means 90 for opposing pivotal movement between the said members in either direction and operating means connected to the pivotal joint between the members.

2. A current collector having a pivotally mounted contact arm comprising two pivotally connected members, resilient means for opposing pivotal movement between the said members in either direction, actuating means for said contact arm connected to the joint 100 between its members and means tending to hold said arm in an inactive position.

3. A current collector having a pivotally mounted contact arm comprising two pivotally connected members, springs directly 105 joining said members and opposing pivotal movement between them in either direction, fluid-pressure-actuated means for holding

the contact arm in operative position and means for moving said arm to an inactive position upon withdrawal of fluid pressure.

4. The combination with a current-collecting device that may engage a supply conductor upon either its upper or its lower face, of a cylinder, a piston located in said cylinder and actuated in one direction by fluid-pressure, a spring also located in said cylinder for actuating said piston in the opposite direction, and a rod connecting the piston to the current-collecting device whereby said device may be held in an inactive position or moved to and held in an active position.

5. In a current collector, the combination with a pivotally mounted contact arm comprising two pivotally connected members, and resilient means for opposing pivotal movement between said members in either direction, of a piston rod connected to the joint between the members, a piston, a cylinder and resilient means for normally maintaining the piston at one end of its stroke.

6. The combination with a two-part contact shoe having a joint between the parts and a double-acting spring serving to oppose relative movement of said parts in either direction, of a spring acting upon said joint to hold the shoe in one extreme position and fluid-pressure-actuated means to oppose the action of said spring.

7. The combination with a pivoted contact shoe having a joint intermediate its ends and a double-acting spring serving to oppose relative movement of the jointed parts in either direction, a spring acting upon said joint to move the shoe in one direction and a fluid-pressure-actuated means for moving the shoe in opposition to the spring.

In testimony whereof, I have hereunto subscribed my name this 10th day of April, 1906.

RAY P. JACKSON.
